UNITED STATES PATENT OFFICE

161,025

COMBINED ELECTRICAL JIG SAW AND SANDER

Elmer L. Hoffmann, Park Ridge, and Allen L. Atkins, Chicago, Ill.; said Hoffmann assignor to said Atkins

Application February 21, 1950, Serial No. 8,044

Term of patent 14 years

(Cl. D93—3)

To all whom it may concern:

Be it known that we, Elmer L. Hoffmann and Allen L. Atkins, citizens of the United States and residents of Park Ridge and Chicago respectively, in the county of Cook and State of Illinois, have invented a new, original, and ornamental Design for a Combined Electrical Jig Saw and Sander, of which the following is a specification, reference being had to the accompanying drawing, forming a part thereof:

Fig. 1 is a perspective view of a combined electrical jig saw and sander, showing our new design.

Fig. 2 is a perspective view of the same on a smaller scale and taken from the side opposite to the view of Fig. 1.

Fig. 3 is a top plan view of the same.

We claim:

The ornamental design for a combined electrical jig saw and sander, substantially as shown.

ELMER L. HOFFMANN.
ALLEN L. ATKINS.
